J. JOHNSON

FORM FOR CONCRETE WALL CONSTRUCTION

Filed Sept. 13, 1922

UNITED STATES PATENT OFFICE.

JAMES JOHNSON, OF SOUTH PASADENA, CALIFORNIA.

FORM FOR CONCRETE WALL CONSTRUCTION.

Application filed September 13, 1922. Serial No. 587,917.

To all whom it may concern:

Be it known that I, JAMES JOHNSON, a citizen of the United States, residing at South Pasadena, in the county of Los Angeles and 5 State of California, have invented new and useful Improvements in Forms for Concrete Wall Construction, of which the following is a specification.

My invention relates to forms for concrete 10 wall construction, and more particularly pertains to a collapsible core form adapted to be disposed between the ordinary side board forms in order that the wall when formed will be cored out to provide ventilating 15 spaces and will be stronger and more economical of construction.

The object of my invention is to provide a core form for the above recited purpose which will be simple, efficient, and cheap 20 and durable of construction, and which may be efficiently braced and held in shape while the cement mixture is being placed around the same, and quickly and easily collapsed and removed after the mixture has become 25 sufficiently set, in order that it may again be utilized when another course of the mixture is laid.

Other objects of my invention will be more fully disclosed in the following specification, 30 reference being had to the accompanying drawings forming a part thereof, in which:

Fig. 1 is a plan view of a portion of a concrete wall showing my invention as it would appear during the construction of the 35 same.

Fig. 2 is a longitudinal section through the same, taken on the line 2—2 of Fig. 1, viewed in the direction indicated by the arrows.

Fig. 3 is a transverse section through the same, taken on the line 3—3 of Fig. 1, viewed in the direction indicated by the arrows.

Fig. 4 is a perspective view of one of the 45 end members of the core form.

Fig. 5 is a perspective view of a toggle brace bar member.

Fig. 6 is a fragmental view of one of the side members of the core form.

The core form 10 is built up of five members, including two end members 11 and 12, which are identical in construction, two side members 13 and 14, which are also identical in construction, and the brace or toggle bar 50 member 15.

The end member 11 is preferably formed

of a rectangular piece of flexible sheet metal which is bent in the shape of a bow and has its edges doubled backward to form the hooks 16. Riveted to the sheet metal and 60 disposed at its edges are the oppositely disposed vertical strengthening angle iron ribs 17, and riveted at the crown of the bow is a vertically disposed angle iron rib 18.

Riveted to the angle iron 18 at its upper 65 and lower ends is an inwardly projecting V shaped brace bar 19, and disposed between said brace bar and one of the angle iron ribs 17 is a cross bar 20. A pair of toggle levers 21 are disposed between the angle irons 17, 70 and comprise the bars 22 and 23 pivoted together at 24 and having their ends pivoted at 25 to said angle irons. The free end of bar 22 is provided with an ear 26 adapted to project over the top edge of bar 23 in order 75 that the toggle may be conveniently manipulated.

The side member 13 is preferably formed of a rectangular piece of sheet metal, the oppositely disposed end edges of which are 80 bent backwardly in parallel relation with its body portion in order to form hooks 27 thereon adapted to engage with the hooks 16 on the members 11 and 12 to form the core member.

The toggle brace bar member 15 comprises the bars 28 and 29 pivoted together at 30 and having notches 31 formed in their ends adapted to engage with the bars 20 of the members 11 and 12 in order to form a 90 continuous collapsible brace between their crowns, the bar 28 being provided with an ear 32 for the purpose of conveniently either locking or breaking the toggle when desired.

By the above recited construction it will 95 be obvious that in order to assemble the core forms it will only be necessary to interlock the hooks 16 of the end members with the hooks 27 of the side members 13, as clearly shown in Fig. 1 of the drawings.

In building the wall the ordinary side boards 33 may be employed, spaced the desired distance apart, and braced in the usual manner, the side boards being of the desired height to form a course. The core 105 forms which are of a corresponding height to the boards 33 are then placed in between the boards in a manner shown in Fig. 1. The cement mixture is then packed between the boards and around the core forms.

After the cement mixture has become sufficiently set, the toggle braces 21 and 15 are 110

broken by a pull upwardly on the ears 26, and the toggle 15 is also broken by a pull upwardly on the ear 32. The breaking of the toggle member 21 will cause the edges 5 of the member 11 to be drawn inwardly toward each other and consequently pull the side member 13 inwardly and free from the cement, and the breaking of the toggle 15 will cause the members 11 and 12 to be 10 drawn inwardly toward each other free from the cement, and also will disengage the hook members 16 and 27, thus collapsing the core form and separating its various members so that they may be readily lifted 15 from the cement wall and be utilized again in the construction of another course.

By constructing the core member in the manner described it will be obvious that its constituent members may be drawn inwardly 20 toward a common center and away from the cement, by means of the toggle members, to collapse the same, and reduce the area thereof; and also to separate the side members from the end members, thus permitting 25 of the removal of the members from the finished wall without difficulty.

What I claim is:

1. A core form, comprising a pair of oppositely disposed end members composed of 30 flexible material and a pair of oppositely disposed side members interlocked with said end members, and means for moving said end members toward each other and disengaging them from the side members.
- 35 2. A core form, comprising a pair of oppositely disposed bow members formed of

sheet metal having hooks formed on their opposed edges, a pair of oppositely disposed side members having hooks formed on their edges adapted to engage with the hooks on 40 the end members, and an expanding and contracting brace bar member disposed between said end members.

3. A core form, comprising a pair of oppositely disposed bow shaped end members 45 formed of sheet metal having adjustable brace bars disposed transversely between their edges, a pair of oppositely disposed side members detachably secured to said bow shaped end members, and an expanding 50 and contracting brace bar member disposed longitudinally and between the crowns of said bow shaped end members.

4. A core form, comprising a pair of oppositely disposed metallic bow members, a pair of metallic side members, the vertical edges of all of said members being provided with interlocking flanges, whereby the members may be detachably secured together, means connected to said bow members for expanding and contracting said members transversely, and a second expanding and contracting means connected to said bow members and disposed in parallel relation to said side members, whereby the 60 assembled core form may be expanded and contracted along its longitudinal axis.

In witness that I claim the foregoing I have hereunto subscribed my name this 25th day of July 1922.

JAMES JOHNSON.
